[57] **CLAIM**

The ornamental design for a circular floral stand, as shown and described.

DESCRIPTION

FIG. 1 is an elevated perspective view of the circular floral stand comprising the present invention with the surface to which it is adhered being shown in ghost lines, but not forming a portion of the subject invention; FIG. 2 is a front side view thereof, the rear side view being a mirror image of the front side view; FIG. 3 is a top plan view thereof, the bottom view being a mirror image of the plan view; and, FIG. 4 is an end view thereof, the opposing end being a mirror image of the end view in FIG. 4.
